UNITED STATES PATENT OFFICE.

LOUIS V. ARONSON, OF NEWARK, NEW JERSEY.

DESIGN FOR A STATUETTE.

SPECIFICATION forming part of Design No. 36,135, dated November 11, 1902.

Application filed September 16, 1902. Serial No. 123,657. Term of patent 8½ years.

To all whom it may concern:

Be it known that I, LOUIS V. ARONSON, a citizen of the United States, residing at Newark, in the county of Essex and State of New Jersey, have invented a new, original, and ornamental Design for a Statuette, of which the following is a specification, reference being had to the accompanying drawings, forming a part thereof.

Figure 1 is an elevation showing one side of the statuette. Fig. 2 is an elevation showing the opposite side, and Fig. 3 is a plan view of the same.

The design comprises a base, a burro mounted on the base and having secured to its back a miner's outfit. The burro is mounted on a rectangular base, the base having slightly-beveled sides and a matted or egg-shelled top. The burro is centrally mounted on the base, and secured to its back is a miner's outfit, comprising a rolled-up blanket secured to its neck and a pan hanging from

the right side thereof. The cradle is so secured as to partially cover both sides of the burro and is held in position by the lasso which encircles the same and is coiled up and secured at the top. A shovel is secured on the left side of the burro and two picks on the right side.

In the drawings, *a* represents the burro; *b*, the base; *c*, the blanket; *d*, the picks; *e*, the shovel; *f*, the pan; *g*, the cradle, and *h* the lasso.

Having thus described my invention, what I claim is—

The ornamental design for a statuette as herein shown and described.

Signed at Newark, in the county of Essex and State of New Jersey, this 13th day of September, 1902.

LOUIS V. ARONSON.
